UNITED STATES PATENT OFFICE.

DAVID R. COLLIER, OF GARDNER, MASSACHUSETTS, ASSIGNOR TO COLLIER-KEYWORTH COMPANY, OF GARDNER, MASSACHUSETTS, A CORPORATION OF MASSACHUSETTS.

CHAIR-IRON.

1,389,186.

Specification of Letters Patent. Patented Aug. 30, 1921.

Application filed December 9, 1920. Serial No. 429,341.

To all whom it may concern:

Be it known that I, DAVID R. COLLIER, a citizen of the United States, residing at Gardner, in the county of Worcester and 5 State of Massachusetts, have invented new and useful Improvements in Chair-Irons, of which the following is a specification.

This invention relates to chair irons for chairs having a rotatable vertically-adjustable seat supported on a hub provided with radiating legs; and it has for its object 10 to provide certain improvements, which I shall subsequently describe, in that type of irons in which the vertical adjustment is afforded by means separate from the spindle to which the head and the spider are secured.

On the accompanying drawings,—

Figure 1 shows in side elevation a portion of a chair having an iron embodying the 20 present invention.

Fig. 2 represents a plan view of the same.

Fig. 3 represents a front view of the iron on a somewhat larger scale.

Fig. 4 represents a section on the line 4—4 25 of Fig. 2, with the spider in normal position.

Fig. 5 represents a section (some parts omitted) on the line 5—5 of Fig. 3.

Fig. 6 represents a section on the line 6—6 of Fig. 3.

Fig. 7 represents the hub in plan view.

With but few exceptions, the various parts of the iron, which I am about to describe in detail, are all formed of sheet metal for purposes of lightness, strength and cheapness, but cast metal parts may be substituted therefor as may be desirable or convenient. I desire to have it understood also that, while the iron which I have illustrated is the best form of the invention now known to 40 me, it may be changed in many of its details without departure from the spirit and scope of the invention as set forth in the appended claims.

The spider comprises a spreader consisting 45 of a yoke-shaped plate having a top bar 10 and depending side bars or arms 11, and angle plates 12 the webs of which fit on the angle formed by the said top plate and side arms. The side arms of the spreader 50 are pivotally connected to a head which is likewise yoke-shaped and is provided with a bottom plate 13 and up-turned side arms or side bars 14. These yoke-shaped mem-

bers are oppositely arranged and the upwardly-projecting side arms of the head lie 55 between the downwardly-extending side arms 11, 11, of the spreader. As they are thus constructed, they may be stamped from a flat strip of metal and bent into shape. The side arms of each of these elements are 60 provided with extensions. A pivot or bar 15 is passed through the extremities of the extensions of the side arms 11 of the spreader, and through the up-standing arms or side bars of the head, for the purpose of pivotally 65 connecting these two elements together, the ends of the pivot bar being up-set or riveted as indicated at 16 in Fig. 3. The head is affixed to the end of an upstanding spindle 17, which preferably, though not necessarily, 70 consists of a solid metal, smooth, cylindrical bar. A cross brace 18, with down-turned ends 19, is secured between the side arms 14 of the head by rivets 20, and it is spaced from the bottom or cross bar 13 of the head 75 so as to provide means for rigidly securing the spindle to the head. It will be observed from an inspection of Fig. 4 that the spindle is passed through the cross bar 13 of the head and through the cross brace 18, 80 and its shouldered upper end is upset or otherwise formed to rigidly engage said cross brace as at 21. The up-standing extensions 22 of the side arms or side bars 14 of the head are formed with a corner 85 23 on which rest the concave trunions 24, 24, of a cross plate 25, which is adapted to rock on the corners as a pivot. Through this plate there is passed a bolt 26, the outer extremity of which passes through a spring 90 plate 27 and is provided with a nut 28 resting against said spring plate. Compression springs 29 are introduced between said spring plate and the depending web 30 of an angle bar, the other web 31 of which is 95 riveted to the under side of the cross bar 10 of the spreader. Normally the pressure of the springs 29 holds the web 30 of the angle plate against the up-standing extensions 22 of the head, but, when the spider is tilted 100 backwardly, as shown in Fig. 5, the extremities of the extension 22 enter slots 33 of the web 31 of the angle plate, and engaging the ends of the slots limit the tilting movement of the spider as will be clearly seen 105 from an inspection of Fig. 5. The usual

seat is secured as usual to the angle arms of the spider, which arms are of the usual construction.

The hub, to which the chair legs 34 are secured, consists of a central sheet-metal tube 35 encircled by channel bars substantially similar to those described in Letters Patent No. 1,287,640, granted to me on December 17, 1918, these angle bars being shown in dotted lines in Fig. 7 at 36. The upper end of the sleeve or tube 35 is passed through the central aperture in a circular plate 37 which forms the top member of the hub, and the ends of the tube are spun or turned outwardly as at 38 so as to overlap the upper surface of said plate as shown in Fig. 4. The tube is beaded as at 39 so that it is rigidly secured to the circular plate 37. The upper ends of the channel bars are secured to this plate 37 in the same manner that the channel bars are secured in the construction described in the Letters Patent aforesaid. The bottom of the hub consists of a plate 40 having radiating arms 41, and it is slipped onto the lower end of the sleeve 37 so as to engage projections 42 extending downwardly from the middle web of the channel bars 36. The legs are held in the channel bars by wood screws 43 passed through the top plate 37 and by screws 44, 45, passed up through the bottom plate 41. As thus described, the hub is substantially similar to the hub illustrated and described in said Letters Patent.

Instead of adjusting the head and the spider relatively to the hub by means of the central spindle, about the axis of which the head rotates, I provide independent means for effecting such vertical adjustment. It will be observed from Fig. 4 that the spindle 17 passes down through the unthreaded portion of the sleeve or tube 35, and is free to rotate therein freely, the contacting surfaces being cylindrical and unthreaded, and the central tube extending a short distance above the top circular plate 37.

Resting on the central tube is a collar 50 which is of the same internal diameter as the tube 35, and which is in sliding engagement with the spindle 17. This collar constitutes the hub of a plate 51 which is placed on the tube and which is held between a rib or bead 52 thereon, and a second collar 53 which is located between the plate 51 and the outwardly spun extremity 54 of the collar 50. The extremity 54 is directly opposed to the extremity 38 of the central tube 35 of the main hub, so that it may rest directly thereon and be supported thereby, but preferably I place between them a fiber washer 55 to reduce wear and friction. If desired, any other form of end-thrust bearing might be interposed between the collar 50 and the end of the tube 35 of the main hub. For purposes of ornamentation and

better appearance, the plate 51 is provided with a down-turned marginal flange or skirt 56 which conceals the parts located between the plate 51 and the top plate 37 of the hub. These two plates are held against relative axial movement by means of a relatively short flanged segment 58 secured to the top plate 37 by rivets 59, as shown in Fig. 7. The small collar 53 is provided with a peripheral flange 60 which takes under the flange of the segment, as shown in Fig. 4, thereby preventing axial dislocation of the plate 51 from the main hub under normal conditions. The plate 51 is not entirely circular. As shown in Fig. 2, it is provided with a lug 61 through which is introduced cylindrical end 62 of a screw bar 63. The threaded portion of this screw bar extends upwardly through a threaded sleeve 64 which is rigidly secured in lugs 65, 66, formed on the cross brace 18 and the bottom cross bar 13 of the head. For the purpose of securing this sleeve in place, it may be beaded as indicated at 68, 69, so as to engage the lugs through which its extremities pass. A cotter pin 70 is passed through the lower extremity of the screw bar so as to engage the under face of the plate 51. The lower portion of the screw bar is reduced in diameter so as to provide a shoulder 71 to engage the plate 51, and, above the plate 51, there is rigidly secured to the screw bar a handle by which it may be rotated. This handle consists of a concave circular plate 72 with a down-turned flange or skirt, into which is forced a flat washer or member 73 which engages the marginal flange or skirt of the member 72 of the handle. The members 73 and 72 are forced together under pressure so that they are securely bound one to the other, and they are likewise forced friction-tight on the unthreaded portion of the screw bar (which is upset to form splines 74), so that, when the handle as thus formed is rotated, the screw is likewise rotated. The screw bar serves to connect the head and the screw-supporting plate, so that they will all rotate with the spindle 17 as a unitary structure, as the spindle 17 rotates in the central tube of the pedestal hub. Whenever desired, the screw bar, however, may be rotated to adjust the spindle and the parts secured thereto relatively to the hub and the pedestal. The rotation of the chair seat and the spider to which it is secured are about the axis of the spindle 17, which is, of course, coincident with the axis of the main pedestal hub. Furthermore, the entire weight of the chair seat, the spindle and all of the parts above the main hub are supported directly on the upper extremity of the central tube of the main hub, and all of the adjusting mechanism is located above the top plate 37 of the main hub. The central tube or sleeve 130

of the hub is rigidly secured to the top and bottom plates of the main hub, and is not rotatable relatively thereto, as a result of which I am able to secure a rigid construction. The rotating element, which engages the main hub, is the solid spindle 17 which passes therethrough, and the collar 50, as stated, is located entirely above the main hub and rests upon the extremity of the non-rotary sleeve or tube which forms an essential element of the hub. Thus the bore of the main hub or the tube which forms a portion thereof is in engagement only with the central spindle 17 which rotates therein. 10

15 While the central spindle 17 acts as a guide post, it is not fixed in the hub, but, as stated, is freely rotatable therein, and is adapted to slide vertically up and down within the hub. The plate 51, with the collar 50 which 20 forms the hub thereof, and which could if desired be formed integrally therewith, constitutes the adjusting screw carrier. It is not essential that this element should be made of sheet metal, although for various 25 purposes this is desirable. However, it is desirable to have it provided with a depending flange 56 to increase its stiffness and prevent its being bent by the downward thrust of the adjustment screw 63 which 30 rests thereon.

Having thus explained the nature of my said invention and described a way of making and using the same, although without attempting to set forth all of the forms in 35 which it may be made or all of the modes of its use, what I claim is:—

1. In a chair iron, a seat-supporting head, a non-rotatable main hub, a spindle fixed to said head and having a sliding and rotatable 40 engagement with the inner wall of said hub, and head adjusting means parallel to said spindle, resting rotatably on said hub and adapted to rotate with said spindle and to slide said spindle in the hub.
  2. In a chair iron, a seat-supporting head, a main hub having a fixed central tubular member, a spindle fixed to said head and slidably and rotatably fitting in said tubular hub member in engagement with the inner wall thereof, a plate rotatably supported 50 on the hub member, and an adjusting screw journaled in said plate outside of the central tubular member and in threaded engagement with said head.
  3. In a chair iron, a seat-supporting head, a main hub having a central tubular member, a spindle fixed to said head and extending downwardly through said tubular member so as freely to rotate and slide therein, a plate resting loosely upon the upper end of the head and in sliding engagement with 60 said spindle, and an upstanding adjusting screw stepped in said plate and having a threaded engagement with said head.
  4. In a chair iron, a pedestal hub having a 65
- central bore, a spindle journaled in said bore to rotate on its axis and to slide vertically in said hub, a seat-supporting head secured to the upper end of the spindle to move up and down therewith, a rotatable member supported on the hub, means to hold said member on said hub without preventing its rotation relatively to the hub, and an upstanding screw journaled in said member and having its upper threaded end in threaded engagement with said head. 70
5. In a chair iron, a head comprising a yoke having a cross bar and upstanding arms, a cross brace parallel to said cross bar and secured to said yoke, and a tubular nut 80 secured to said cross bar and said cross brace; an adjusting screw in engagement with said nut; and a spindle engaged with the cross bar and the cross brace of said head. 85
6. In a chair iron, a head comprising a yoke having a cross bar and upstanding arms, a cross brace parallel to said cross bar and secured to said yoke, and a tubular nut 90 passing through and secured to said cross bar and said cross brace. 90
7. In a chair iron, a pedestal hub, a spindle passing rotatably and slidably through the bore of said hub, a seat-supporting head located on the upper end of the spindle and 95 fixed against axial movement relatively thereto, a rotatable plate having a hub slidably engaging said spindle and resting on the top of the pedestal hub, a nut on the said head, an adjusting screw seated on said plate 100 and in threaded engagement with said nut, and a member for holding said plate against vertical movement relatively to said hub without preventing its rotation. 100
8. In a chair iron, a pedestal hub, a spindle passing rotatably and slidably through the bore of said hub, a seat-supporting head located on the upper end of the spindle and fixed against axial movement relatively thereto, a rotatable plate having a hub slidably 110 engaging said spindle and resting on the top of the pedestal hub, a nut on the said head, an adjusting screw seated on said plate and in threaded engagement with said nut, and means located between said rotatable 115 plate and said pedestal hub, having an interlocking engagement with the hub of said plate. 115
9. In a chair iron, a pedestal hub having a tubular bore, a centrally-apertured rotatable plate resting on said hub, an anti-friction thrust bearing interposed between said plate and said hub, a spindle passing through and in longitudinally slidabile engagement with said bore and the aperture 120 in said plate, and means for interlocking said plate with said hub. 120
10. In a chair iron, a pedestal hub having a central tube, a rotatable adjustment-screw- 125 supporting member having a hub alined 130

with and supported by said central tube, and a locking member on the pedestal hub having an interlocking engagement with the hub of said adjustment-screw-supporting plate.

11. In a chair iron, a pedestal hub having a central tube, a rotatable adjustment-screw-supporting member having a hub alined with and supported by said central tube, 10 a locking member on the pedestal hub having an interlocking engagement with the hub of said adjustment-screw-supporting plate, and a head-supporting spindle rotatably and slidably engaged with the hub of 15 said plate and the central tube of the pedestal hub.

12. In a chair iron, a pedestal hub comprising a central tube and a top plate secured thereto, a seat-supporting head, a 20 spindle fixed thereto against relatively axial movement, a nut on said head, a rotatable plate having a hub through the bore of which the spindle extends, said last-mentioned hub resting on and being supported 25 by the central tube of the pedestal hub, a locking member on the top plate of the pedestal hub engaging the hub of the rotatable plate, to prevent axial separation of said plate and said pedestal hub, and an up- 30 standing screw bar seated in said plate and having a threaded engagement with said head.

13. In a chair iron, a head having spaced 35 parallel bars, a spindle located in apertures in said bars, a tubular nut parallel to said spindle and having its ends located in apertures in said bars, and means for holding said tubular nut against axial movement relatively to said bars.

40 14. In a chair iron, a head having spaced parallel bars, a spindle located in apertures in said bars, a tubular nut parallel to said

spindle and having its ends located in apertures in said bars, and external beads on said nut engaging said bars to hold said nut 45 against axial movement.

15. In a chair iron, the combination with a spindle, an adjusting screw parallel therewith, a pedestal hub in which said spindle is journaled and a head on the spindle having a nut with which said screw is engaged, 50 of a screw-supporting plate, a collar forming the hub of said plate and having a bead above the plate, and a second collar on the hub below the plate and clamping it against 55 said bead, said plate resting on the pedestal hub and rotatable relatively thereto.

16. In a chair iron, the combination with a spindle, an adjusting screw parallel therewith, a pedestal hub in which said spindle 60 is journaled and a head on the spindle having a nut with which said screw is engaged, of a screw-supporting plate, a collar forming the hub of said plate located on said spindle, and seated on the pedestal hub, said 65 collar having a flange, and a locking member on the pedestal hub taking over said flange, to permit said plate to rotate and yet to hold it against axial movement relatively to said pedestal hub. 70

17. In a chair iron, the combination of a pedestal hub, a spindle rotatable and slidable in the bore of said hub, a seat-supporting head secured to the upper end of the spindle to rotate and to move up and down therewith, a plate rotatably supported on top of the pedestal hub and located above the horizontal planes thereof, and an adjusting screw stepped in said plate and in threaded engagement with said head. 75 80

In testimony whereof I have affixed my signature.

DAVID R. COLLIER.
